(57) **CLAIM**

The ornamental design for a marine electronic device display, as shown and described.

DESCRIPTION

FIG. 1 is a front perspective view of a marine electronic device display showing our new design.

FIG. 2 is a rear perspective view of the marine electronic device display of FIG. 1.

FIG. 3 is a front view of the marine electronic device display of FIG. 1.

FIG. 4 is a rear view of the marine electronic device display of FIG. 1.

FIG. 5 is a left side view of the marine electronic device display of FIG. 1.

FIG. 6 is a right side view of the marine electronic device display of FIG. 1.

FIG. 7 is a top view of the marine electronic device display of FIG. 1; and,

FIG. 8 is a bottom view of the marine electronic device display of FIG. 1.

The broken lines are included for the purpose of illustrating portions of the marine electronic device display and form no part of the claimed design.
